UNITED STATES PATENT OFFICE

2,418,647

THERMOSTATIC SWITCH

Richard H. Jordan, Mansfield, Ohio, assignor to
Dominion Electrical Manufacturing, Inc., a
corporation of Ohio

Application May 18, 1944, Serial No. 536,287

4 Claims. (Cl. 200—137)

1

My invention relates in general to temperature responsive devices, and more particularly to temperature controlling devices which may be actuated as a switch to an off-position.

An object of my invention is to provide a manually adjustable controlling device for a thermostatic switch whereby fine differences of temperature adjustments can be obtained in the low temperature ranges.

Another object of my invention is to provide a switch for a temperature controlling device which is positive in its interrupting action.

Another object of my invention is to provide a temperature controlling device for electrically heated appliances in which a sudden endwise or axial movement of the control button is obtained when the button is rotated to the off position in order that psychological assurance is given to the user that the current is disconnected.

Another object of my invention is the provision of a temperature controlling device in a thermostatic switch which is rugged in construction and has few moving parts.

Another object of my invention is to provide a controlling device for a thermostatic switch which is simple in construction to provide manufacturing economy.

Other objects and a fuller understanding of my invention may be had by referring to the following description and claims, taken in conjunction with the accompanying drawing, in which:

Figure 1 is a side elevational view of a thermostatic switch in which my controlling device may be used, with the top part of my controlling device shown extending therefrom;

Figure 2 is a cross-sectional view of Figure 1;

Figure 3 is a top view of the actuating control knob of my invention;

Figure 4 is a projected view of the controlling cam bushing used in my invention, as seen projected on a flat surface;

Figure 5 is a top view of a cam bushing used as an elevational or endwise control mechanism in my invention;

Figure 6 is a side view of the cam bushing used as an elevational or endwise control mechanism in my invention;

Figure 7 is a top view of the stem which passes through a bushing and contacts a movable part of the thermostatic switch in which my invention is used; and

Figure 8 is a side view of the stem used in my invention and illustrates a tab extending from the side thereof.

With reference to Figure 1 of the drawing, I

2

illustrate a type of thermostatic switch with which my invention will operate. The thermostatic switch illustrated is similar to that shown in Barnes, Patent No. 2,217,328. However, my control invention will operate with other kinds of thermostatic switches.

As illustrated in Figure 2, I show a thermostatic switch having a case 20, a base member 30, a steel spring member 24 supporting an insulating button 22 and two resilient conducting arms 23 and 24 with contact points 25 and 26 respectively mounted thereon. My controlling device is also illustrated in the Figure 2 and is shown generally by reference character 31. The controlling device 31 may be located with most of its component parts located externally of the case 20 as illustrated.

The spring member 24 is secured to the base member 30 by any suitable means, such as by rivets 38 as illustrated. The resilient conducting arms 23 and 24 are mounted within the case 20 and directly above the insulating button 22, and are separated one from the other at their extreme ends by insulating material or blocks as shown by reference character 27. The contact points 25 and 26 do not touch unless they are constrained by outside influence. As is illustrated in Figure 2, the arm 23 is connected to an outside conductor 28, and the arm 24 is connected to an outside line 29.

The spring member 24 has a very low coefficient of thermal expansion, whereas the base member 30 has a very high coefficient of thermal expansion. Therefore, as the temperature of the surroundings of the members 30 and 24 increases, the member 30 tends to expand at a greater rate than the member 24. The result of this unequal expansion with increasing temperature is that the insulating bottom 22 is steadily lowered towards the member 30, and the resilient conducting arm 23 is disposed to follow therealong. As long as the contact members 25 and 26 are forced to touch one another a current passes from the outside conductor 28 through the resilient arm 23, through the contact point 25, into the contact point 26 and out through the resilient arm 24 to the outside conductor 29. This flow of current is possible as long as the resilient arms 23 and 24 are close enough together to allow the contact points 25 and 26 to touch. As hereinbefore described, the resilient arm 23 is disposed to move downwardly with each increase in temperature following the insulating button 22 and thereby cause a disconnection between the contact points 25 and 26 at some temperature as prede-

terminated by the position of the resilient arm 24 and its contact point 26.

My invention consists of a device to accurately control the position of the resilient arm 24. My invention is shown generally by the reference figure 31 and consists of a holding jacket or sleeve 32, a slotted cam bushing 33, a stem 34, and a control knob 35. An assembled control device of the type applying to my invention is shown illustrated in Figure 2 with the control knob 35 of the device positioned above an outside case plate 36 of the appliance in which it is operating. The stem 34 of my controlling device passes through an opening in the case 36, through the slotted cam bushing 33 which is positioned within the holding sleeve 32, and contacts the resilient arm 24.

The holding sleeve 32 has a circular opening therethrough of appropriate dimensions to accommodate the slotted cam bushing 33, and is secured to the case 20 by any suitable means such as shown by peened tips or rim 37.

The slotted cam bushing 33, which serves as a cam member may be constructed from a flat piece of material and rolled into shape for insertion in the holding member 32. Figure 4 illustrates the slotted cam bushing 33 in a flat strip of material prior to being rolled into a cylindrical sleeve and is provided with an opening 38 and a notch 39. As noted, in the illustration, the slot 38 is divided into three sections: A—C, C—B, B—D. The steep part of the slot 38 as shown in Figure 4 from D—B, is to be used for giving the positive off-position movements, the second intermediate part of the slot as shown in Figure 4 from B to C is to be used for regulating the high range of temperature as for example, from cotton to silk when installed in an electric sadiron. A third part of the slot 38 as shown in Figure 4 from C to A is to be used for giving more delicate adjustments of the lower heat range, as for synthetic fibers. The notch 39 is provided for convenience of holding the slotted cam bushing in a predetermined fixed position during assembly. By rolling the strip of material, as shown in Figure 4, into a cylindrical form, a cylinder as illustrated in Figure 5 is produced. The cylinder as thus formed and described constitutes the slotted cam bushing 33. An elevational view of the slotted cam bushing 33 as formed and described is shown in Figure 6.

The stem 34 is composed of a hollow tube 40, an external tab 41, an adjustment screw 42 and an insulating bead 43. The tab 41 may be provided by any convenient means, such as by pinching or squeezing a part of the external circumference of the tube 40 into the tab 41. The adjustment screw 42 is provided to adjust or initially calibrate the position of the insulating bead 43 within the interior of the stem 34, so that the correct indications are given by the control knob or control dial.

A type of control knob which may be used with my invention is shown illustrated in Figure 3, and in cross-section in Figure 2. An upright fin or rib portion 44 serves to provide a convenient finger tip grip, the circular part 45 is used as a convenient indicator on which to mark various temperature ranges. A set screw and recess is provided, as shown at 47 of Figure 2, for the purpose of attaching the control knob 35 to the stem part 34.

In the thermostatic switch such as illustrated generally by the reference character 20, if the temperature surrounding the parts 21 and 30

lowers, the button 22 carried on the part 21 is disposed to rise and push the resilient arm 23 and the contact point 25 upward toward the contact point 26 on the arm 24. At any temperature lower than that required to bring the contact points 25 and 26 into contact, an excess pressure is caused by the raising of the insulating button 22.

The excess pressure thus produced is absorbed by bending of the resilient arm 23. Bending of the arm 23 causes no difference in the operation of the thermostatic switch. Conversely, as the temperature surrounding the parts 21 and 30 increases, the insulating button 22 is lowered and the resilient arm 23 follows therewith until contact is broken between the contact points 25 and 26. Therefore, thermostatic control of the temperature surrounding the parts 21 and 30 is maintained by setting the position of the resilient arm 24 and the contact point 26 thereon. From the description given it is seen that a fine adjustment of the temperature desired must of necessity be brought about by a fine adjustment of the resilient arm 24 and the contact point 26. Furthermore, whenever it is desired to assure complete separation of the contact points 26 and 25 to completely remove the appliance from use, it is desirable to permit the resilient arm 24 to raise beyond any possible contact with the resilient arm 23.

For operation, my invention is installed on the thermostatic switch by fastening the holding jacket or sleeve 32 to the case 20 by means of peened tips or rims 37. The slotted cam bushing 33 is inserted within the opening of the holding jacket 32 and securely held therein. I prefer to hold the cam bushing 33 in the holding jacket 32 by a snug, press fit between the parts. However, it is understood that these parts may be welded, brazed, or fastened by other means to hold the cam bushing 33 in the holding jacket 32. The stem part 34 is passed through the interior of the slotted cam bushing 33 with the tab 41 guided into the slot 38 thereof. The controlling knob 35 is secured to the upper end of the cam part 34 by means of the side securing means 41. The insulating bead 43 is inserted in the end of the stem 34 and is held in position by the force exerted on it by the resilient arm 24.

In operation, the tab part 41 is positioned within the slot 38 of the slotted cam bushing 33 such that it will be at the position indicated by the letter A within the slot as shown in Figure 4. When the tab 41 is in the position described, the stem part 34 will be forced against the resilient arm 24 such that both stem 34 and the resilient arm 24 will be positioned downwardly toward the resilient arm 23 a maximum distance. From this position only a slight cooling below the maximum temperature for which the thermostatic switch is designed will cause the insulated button 22 to force the resilient arm 23 and the contact point 25 upward enough to cause contact between the points 25 and 26, and thereby cause reheating of the appliance in which the thermostatic switch is operating. As the tab part 41 is moved circumferentially about the slotted cam bushing 33, that is, as the tab part 41 progresses from the position as indicated by A in Figure 4 and along the slot 38 to the position B as indicated in the slot 38 on Figure 4, the stem part 34, the controlling knob 35, and the resilient arm 24 with its contact button 26 are disposed to rise away from the resilient arm 23. It is noted, that the slot 38 slopes upwardly at a very slow rate

between the reference characters A and C of Figure 4. The angle of slope between C and B is slightly more than the angle of slope between A and C as shown in Figure 4.

Continuation of the slot 38 at the same angle of slope as the part of the slot between the points C and B will not ordinarily provide enough rise in the resilient arm 24 to give an off switch movement. Therefore, the steep part of the slot 38 from D to B serves to allow sudden movement of the stem 34 and the control knob 35 under the spring action of the resilient arm 24. The large endward or axial movement described allows the contact point 26 to rise beyond any possible chance of contact with the point 25. Further, the described sudden and pronounced endward or axial movement of the control knob 35 gives the user of the appliance complete psychological assurance that the iron or other appliance is disconnected from the supply source.

To make adjustments of temperature from the lowest temperatures for which the combination of the thermostatic switch controlling device is designed, an operator need merely turn the control knob 35 in such a manner that the tab part 41 is moved along the slotted part 38 of the cam bushing part 33 from the position marked A in Figure 4 through the position marked C and on to the highest temperature position at the point marked B. A slight further movement of the control knob 35 past the position marked B in Figure 4 will bring the tab part 41 into position to be moved freely up the steeply sloping portion of the slot 38. When the tab part 41 is in the off position described, the spring action of the resilient arm 24 is free to move the stem part 34, and the knob 35 upward with a sudden action for a distance far greater than the total distance moved as a result of the complete rotation of the tab 41 from the position A to B within the slot 38. This sudden action assures the user that the appliance is turned off, and at the same time allows the resilient arm 24 and its contact button 26 to be completely removed from all possible contact with the contact 25 of the resilient arm 23.

To return the appliance to use, the operator needs merely apply a small amount of twisting action to the control knob 35. This small amount of force will cause the tab to be deflected downwardly along the steep part of the slot 38 and pull the stem part 40 and the control knob 35 therealong. The insulating bead 43 thus forces the resilient arm 24 with its contact point 26 downwardly and causes contact to be made between the contact points 25 and 26.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A thermostatic switch comprising, first and second relatively movable contact parts normally resiliently disposed to separate from each other, temperature responsive means to urge said first contact part against said second contact part, substantially annular cam means supported relative to said contact parts, a control stem manually rotatable and axially movable within said cam means to position said second contact part in contactable relation with said first contact

part, said cam means having a regulating "on" portion disposed at a slight angle with reference to a line normal to the longitudinal axis of the stem, said cam means having a relieved "off" portion disposed at a steep angle with reference to a line normal to the axis of the stem, projecting means carried by said stem to cooperate with said cam means, said second contact part urging said stem axially of said cam means and holding said projecting means against said regulating "on" portion of the cam means when the stem is rotated to bring the said projecting means in alignment with the regulating "on" portion whereby turning of the stem regulates the position of the second contact part with respect to the first contact part, said stem thereby holding said second contact part in contactable relation with said first contact part, said second contact part suddenly urging said stem axially of the cam means when the stem is rotated to bring the projecting means in alignment with the relieved "off" portion of the cam means, said second contact part thereby resiliently moving away from contactable relation with said first contact part.

2. A switch comprising, first and second relatively movable contact parts normally resiliently disposed to separate from each other, support means for supporting said contact parts, cam means carried by said support means and disposed relative to said contact parts, a control stem manually rotatable and movable endwise with reference to said cam means for positioning said second contact part in contactable relation with said first contact part, said cam means having a relieved "off" portion, projecting means carried by said stem to cooperate with said cam means, said second contact suddenly urging said control stem endwise with reference to said cam means when the control stem is rotated to align the projecting means with the relieved "off" portion of the cam means, said second contact part thereby resiliently moving away from contactable relation with said first contact part.

3. A switch comprising, a first contact part, a relatively movable second contact part normally resiliently disposed to separate from the first contact part, cam means supported relative to said second contact part, a control stem manually rotatable and movable endwise with respect to said cam means for positioning said second contact part in contactable relation with said first contact part, said cam means having a relieved "off" portion, projecting means carried by said stem to cooperate with said cam means, said second contact part suddenly urging said control stem endwise with reference to said cam means when the control stem is rotated to align the projecting means with the relieved "off" portion of the cam means, said second contact part thereby resiliently moving away from contactable relation with said first contact part.

4. A switch comprising, a first contact part, a relatively movable second contact part normally resiliently disposed to separate from the first contact part, support means for supporting said contact parts, a control stem manually operable and movable endwise with reference to said support means for positioning said second contact part in contactable relation with said first contact part, said support means and said control stem having cam means and cam rider means, said cam means having a relieved "off" portion, said second contact part suddenly urging the control stem endwise with reference to the support means when the cam rider means is aligned

with the relieved "off" portion of the cam means, said second contact part thereby resiliently moving away from contactable relation with said first contact part.
